 and in Great Britain November 27, 1931

8 Claims. (Cl. 181—31)

The present invention relates to loudspeakers. In loudspeakers comprising a vibratory sound radiating diaphragm it is known that, in order to obtain adequate response at the lower acoustic frequencies, it is necessary to make the length 5 of the path by which pressure waves from the back of the diaphragm can reach the front of the diaphragm at least of the same order of magnitude as one quarter of the wavelength of the 10 lowest frequency to be radiated. For this purpose diaphragms have been surrounded by flat rigid baffles. It will be evident that flat baffles, to be efficient, must be of considerable size and therefore cumbersome.

15 It has also been proposed, therefore, to mount a loudspeaker diaphragm in an aperture in the front wall of a box and in some cases the back of the box has been left open. The inside of such boxes has also been lined with sound damping 20 material such as felt.

Loudspeakers of this kind suffer from so-called 25 box resonance effects due to reflections from the walls of the box and also to resonance of the air column enclosed within the box. The thickness 30 of the lining of sound damping material hitherto used has been far too small to prevent resonance due to wall reflections and in any case there has been air column resonance due to reflections from the plane of the back of the box where there is a 35 sudden transition from an enclosed air column to the free air. This air column resonance is selective, that is to say it occurs at one or more definite frequencies and the response at these frequencies is thereby unduly increased (or in the case of an anti-resonance decreased) at the expense of neighbouring frequencies.

40 It has also been proposed to fill the space behind the diaphragm with damping material, but this leads to lack of sensitivity at low frequencies due to excessive damping of the movement of the 45 diaphragm at such frequencies.

It is an object of the present invention to provide improved means whereby the length of the 50 path between the front and the back of the diaphragm may be made relatively large without the use of a baffle of large frontal area and without introducing appreciable selective box resonance effects.

According to the present invention, there is 55 provided upon one side of a diaphragm, such as the sound radiating diaphragm of a loudspeaker, an air chamber wholly or partially bounded by sound damping material of such nature and thickness that a large proportion of the sound energy 60 of lower frequencies falling upon the material is

absorbed thereby, the air chamber flaring from the diaphragm outwards.

The air chamber is preferably of considerable size.

The invention is illustrated by way of example 60 in the accompanying drawing, in which

Fig. 1 is a perspective view of one embodiment and Fig. 2 is a part sectional plan view of the embodiment in Fig. 1,

Figs. 3 and 4 are views, corresponding to those 65 of Figs. 1 and 2, of a further embodiment of the invention.

Referring to Figs. 1 or 2, the diaphragm 1 of a 70 loudspeaker is mounted in known manner in an aperture in the front wall 2 of a box, the back of the box being left open. The inside of the box is lined with a thick layer of damping material 3,

for example the material known as slag wool or rock wool. This material is of a fibrous nature and is kept in place by means of a former 4 constructed of wire mesh covered with thick muslin 75 to retain the fine particles of the wool and yet to offer little obstruction to the passage of sound waves. The cross-sectional area of the air chamber increases approximately logarithmically from the diaphragm outwards. Thus, the thickness of 80 the damping material at the smaller end of the air chamber is equal to the distance of the edge of the diaphragm from the inside of the box, and may be comparable with the diaphragm diameter 85

for example, and the thickness flares down to nothing at the end remote from the diaphragm. The thickness is therefore greatest where the sound pressures are highest and resonance due to reflection from the side walls of the chamber is 90 substantially prevented. Further, owing to the flared shape of the air column behind the diaphragm, the air column resonance is made much less selective of particular frequencies than if it were not flared and the flaring also reduces resonance due to reflections from the mouth of the air chamber.

A further advantage of the association of a 95 flared air column of the kind described with a diaphragm, particularly when the diaphragm 100 mounting is such that the resonant frequency of the mass of the diaphragm and the stiffness of its mounting is low, is that the air column provides a further range of stiffnesses which, associated with the diaphragm mass, provide resonant 105 systems over a range of frequencies which is not normally adequately responded to. Furthermore, owing to the walls of the chamber being of damping material, a certain amount of damping is provided for these resonant systems. This range of 110

frequencies is usually between the fundamental natural frequency of vibration of the diaphragm on its mounting and the middle frequencies. Since this resonance is provided over a range of frequencies, it is not objectionable as in the case of selective resonance, that is to say relatively sharp resonance at one or more distinct frequencies.

If desired an air column of the kind described may be provided upon both sides of the diaphragm.

10 The rates of flare and the inlet areas of the two chambers may be the same or they may be made different.

The back of the air chamber may be covered either with a thick layer of damping material or 15 with material which does not appreciably affect the passage of sound waves, such as thin fabric.

In another arrangement shown in Figs. 3 and 4, the top and bottom of the box are omitted so that there remain the front and the two sides. These 20 sides are lined with damping material to form a trough shaped air chamber increasing in width from the front of the box backward. The thickness of the damping material at the front wall 2 may be made greatest in the neighbourhood of 25 the diaphragm as indicated by the dotted lines in Fig. 3.

With this arrangement, the height of the structure is preferably made considerably greater than the breadth in view of the absence of the top and 30 bottom and, if desired, the diaphragm may be arranged nearer the bottom than the top so that the advantage is taken of the floor acting as the bottom of the box. Further, the sides of the structure may be hinged to the front, somewhat as in 35 a fire screen, or they may be fixed at an obtuse angle to the front.

We claim:

1. A device for association with a sound radiating diaphragm comprising a body of sound 40 damping material having a flaring passage therethrough and a lining for said passage, said lining offering little obstruction to the passage of sound waves, and being adapted to retain said material in position, the thickness of said material at 45 the smaller end of said passage being not less than one-half the diameter of the smaller end of said passage and decreasing substantially to nothing at the larger end of said passage.

2. A device for association with a sound radiating diaphragm comprising a body of sound 50 damping material having a substantially logarithmically flaring passage therethrough and a lining for said passage, said lining offering little obstruction to the passage of sound waves, and 55 being adapted to retain said material in position, the thickness of said material at the smaller end of said passage being not less than one-half of

the diameter of the smaller end of said passage.

3. A loud speaker cabinet comprising a substantially rectangular box having an apertured front wall, and a body of sound damping material in said box, said body having its inner surface shaped to form an air chamber increasing progressively in diameter in a rearward direction from the aperture in said front wall, said body having its outer surface adjacent the interior surface of the walls of said box.

4. An acoustic instrument comprising a box having an apertured front wall and four side walls, a diaphragm vibratably mounted in the aperture in said front wall and, upon the inside of said side walls, sound damping material the thickness of which decreases from the neighbourhood of the diaphragm backwards.

5. An acoustic instrument comprising a box having an apertured front wall and four side walls, a frusto-conical diaphragm vibratably mounted in the aperture in said front wall, actuating means for said diaphragm located within said box and upon the inside of said side walls, sound damping material the thickness of which decreases from the neighbourhood of the dia- 100 phragm backwards.

6. An acoustic instrument comprising a structure having an apertured front wall and two side walls, a diaphragm vibratably mounted in the aperture in said front wall and, upon the inside 105 of said side walls, sound damping material the thickness of which decreases from the neighbourhood of the diaphragm backwards.

7. An acoustic instrument comprising a box having an apertured front wall and four side 110 walls, a diaphragm vibratably mounted in the aperture in said front wall and, upon the inside of said side walls, fibrous sound damping material the thickness of which decreases from the neighbourhood of the diaphragm backwards, said 115 damping material being covered with a material adapted to retain said damping material and to offer little obstruction to the passage of sound waves.

8. An acoustic instrument comprising a structure having an rectangular apertured front wall 120 of greater height than breadth and two side walls one associated with each of the longer sides of said front wall, a diaphragm vibratably mounted in the aperture in said front wall and, upon the 125 inside of said side walls, sound damping material the thickness of which decreases from the neighbourhood of the diaphragm backwards.
